US00D757053S

(12) **United States Design Patent**
Nadiadi et al.

(10) **Patent No.:** US D757,053 S
(45) **Date of Patent:** ** May 24, 2016

(54) **DISPLAY SCREEN OR PORTION THEREOF
WITH GRAPHICAL USER INTERFACE**

(71) Applicant: **Level 3 Communications, LLC**, Broomfield, CO (US)

(72) Inventors: **Yunas Nadiadi**, Superior, CO (US); **Paul Farnsworth**, Castle Rock, CO (US); **Jeff Storey**, Boulder, CO (US); **Ajit Kumar Rao**, Broomfield, CO (US); **Eric David Gundersen**, Broomfield, CO (US); **Allen Edward Dixon**, Erie, CO (US); **Sanjiv Kumar**, Erie, CO (US); **Rene Grippo**, Boulder, CO (US); **Luke Patrick Philips**, Denver, CO (US); **Rajiv Kumar Singh**, Thornton, CO (US); **Christopher John Cuttitta**, Golden, CO (US)

(73) Assignee: **LEVEL 3 COMMUNICATIONS, LLC**, Broomfield, CO (US)

(**) Term: **14 Years**

(21) Appl. No.: **29/441,465**

(22) Filed: **Jan. 4, 2013**

(51) LOC (10) Cl. **14-04**

(52) U.S. Cl.

USPC **D14/486**

CLAIM

The ornamental design for a display screen or portion thereof with graphical user interface, as shown and described.

DESCRIPTION

FIG. 1 is a front view of a first embodiment of a display screen or portion thereof with graphical user interface showing our new design; and,

FIG. 2 is a front view of a second embodiment thereof.

The broken lines shown in FIGS. 1 and 2 represent portions of the display screen or portion thereof with graphical user interface that form no part of the claimed design.

1 Claim, 2 Drawing Sheets
